[57] CLAIM

The ornamental design for electric motor rotator for
Christmas tree ornaments, as shown and described.

DESCRIPTION

FIG. 1 is a perspective view of an electric motor rotator
for Christmas tree ornaments showing my new design,
the broken line drawing is for illustrative purposes only
and forms no part of the claimed design;

FIG. 2 is a top plan view thereof;

FIG. 3 is a front elevational view thereof;

FIG. 4 is a bottom plan view thereof; and,

FIG. 5 is a side elevational view thereof.
